UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 14,022, dated July 3, 1883.

Application filed May 16, 1883. Term of patent 3½ years.

To all whom it may concern:

Be it known that I, ARTHUR L. HALLIDAY, of New York, in the county and State of New York, have invented a new and original Design 5 for Carpets, of which the following is a specification.

The accompanying photograph illustrates my new design for carpets.

This invention relates to a new design for 10 carpets, oil-cloths, and analogous fabrics; and it consists of the new ornamentation of parts hereinafter more fully pointed out.

A band, *p*, divides the carpet into an upper part, *A*, and a lower part, *B*. The said band 15 *p* contains a series of rectangles, but is, by a bar, *r*, that has an angular bend in it, as shown, disjointed in the direction of its length. The upper part, *A*, of the carpet contains representations *a* of fanciful flowers, on straight stems, 20 that have leaves *b*, also a part of a sunflower, *d*, all of which are of substantially the same design as is described in application marked "C," filed by me at the same time with this. The lower part, *B*, of the carpet has a border, 25 *C*, at its lower end. Above this border, in the body of the part *B*, is a floral branch, *e*, having star-flowers *f*, and another floral branch,

g, having flowers *h*. A series of rosettes, *i*, are interspersed between the floral decorations *e* and *g*. The border *C* has an upper stripe, 30 *j*, containing mottled V-shaped figures, and a lower stripe, *k*, containing rosettes *l* and mottled figures *m*.

I claim—

1. The design for carpets, consisting of the 35 figures *e* *f*, substantially as shown.
2. The design for carpets, consisting of the figures *e*, *f*, *g*, *h*, and *i*, substantially as shown.
3. The design for carpets, consisting of the figure *j*, substantially as shown. 40
4. The design for carpets, consisting of the figures *l* *m*, substantially as shown.
5. The design for carpets, consisting of the figures *e* *f* *g* *h* *i* *j* *l* *m* substantially as shown.
6. The design for carpets, consisting of the 45 figures *a*, *b*, *d*, *p*, *r*, *e*, *f*, *g*, *h*, *i*, *j*, *l*, and *m*, substantially as shown.
7. The design for carpets, consisting of the figures *e*, *f*, *g*, *h*, *i*, *p*, and *r*, substantially as shown.

ARTHUR L. HALLIDAY.
